UNITED STATES PATENT OFFICE.

MAURICE E. WRIGHT AND ALFRED M. BRADEN, OF GIBBS, IDAHO.

SETWORKS.

Application filed May 1, 1925. Serial No. 27,186.

Our present invention relates to improvements in set works applied to the carriage of saw mills for use in sawing lumber for the purpose of securing accuracy in adjustment with regard to the width of the lumber to be cut, and for maintaining the adjusted parts in rigid set position during the cutting operation.

In the set works now in use difficulty is encountered in retaining or locking the set works against recoil of movement of the ratchet wheel of the set works. To prevent any rebound or recoil of the parts when operating upon lumber, a locking pawl is now employed for the ratchet wheel, and a handle or lever is secured to the shaft of the pawl for controlling the pawl. A spring is employed to hold the pawl against the ratchet wheel of the set works to prevent retrograde movement of the ratchet wheel. This means of stopping and locking the ratchet wheel has proven futile.

By the utilization of the device of our invention we provide means whereby the pawl and ratchet wheel co-act to positively stop and lock the wheel against recoil or rebound.

The invention consists in certain novel combinations and arrangements of parts as will hereinafter be more fully set forth and claimed.

In the accompanying drawings we have illustrated one complete example of the physical embodiment of our invention wherein the parts are combined and arranged in accordance with the best mode we have so far devised for the practical application of the principles of our invention.

Figure 1 is a perspective view showing at the rear and top of the controlling column of the carriage sufficient of the set works to illustrate the application thereto of the device of our invention.

Figure 2 is an enlarged top plan view of a portion of the set works and illustrating the use of our stop and lock device.

Figure 3 is an enlarged perspective view of the lock device of our invention detached.

Figure 4 is a detail plan view partly in section showing a portion of the stop and lock device.

In order that the general assembly and relation of parts may readily be understood I have illustrated in Figure 1 the upper portion of the column or stand 1 which is carried by the saw carriage, and in which

column the set shaft 2 is journaled in the column for controlling the set works. This controller shaft 2 is geared to a horizontal set shaft not shown, and the latter shaft as 60 will readily be understood by those skilled in the art is connected in approved manner to impart the required motion to set and re-cede the knees of the sawing machine. The ratchet wheel 3 of the set works is carried by the controller shaft 2, and a brass setting dial 4 in the form of a disk is geared to the controller shaft to indicate the distance of the knees from the saw. The setting arm 5 swings freely around the ratchet wheel and 70 carries a grip block 6 which is locked into the ratchet teeth 7 when setting the machine for various sizes of lumber. 65

An automatic holding pawl 8 which engages the teeth of the ratchet wheel is used 75 to prevent recoil of this wheel when the set is completed.

The device of our invention co-operates with this pawl to stop and lock the ratchet wheel 3 in set position for preventing rebound or recoil of the wheel. 80

The pawl is carried by a vertically disposed shaft 9 journaled in the radially arranged plate 10, and a pawl lever 11 on the shaft is connected by a cord or other flexible 85 connection to the set lever indicated at 12 in Figure 1 in which the cord is also indicated as 13.

In equipping the pawl lever for use with the device of our invention we provide an 90 actuating pin 14 which is rigid with and projects from the underside of the pawl lever and engages with the locking device for retaining the pawl lever and its pawl in set position. 95

The stop and lock device is located in position on the radial plate 10 so that the locking pin 14 may swing within the device as the pawl lever is moved to lock the pawl to or unlock it from the ratchet wheel 3. 100

An attaching plate 15 which is fixed to the radial plate 10 supports the device through a pair of posts 16 and 16' and on these posts are pivoted two normally parallel levers 17 and 18 that are joined by a 105 bolt 19 having a spring 20 and lock nuts 21, the latter on its free end. The bolt is carried by the lever 18 and extends through a slot in the lever 17, the spring 20 being interposed between the outer side of the lever 17 and the nuts 21 to insure a resilient pressure on the lever 17 to hold the levers 110

in normal parallel position as in Figure 4. The nuts 21 may be turned to vary the tension of the spring and thus vary the resilient connection between the two levers 17 and 18 which frictionally engage the lock pin 14 between them, but at the same time permit the pin to move between them when the pawl lever is turned.

The swinging movement of the locking pin is limited by a detent block 22 carried at the free end of the lever 17, the end of the lever being turned or bent as at 23 to afford a support for the block that is bolted to the lever.

Located within the space between the two levers is a locking block or plate 24 which is adjustable longitudinally of the lever 18 to which it is attached by bolts 25 passing through slots 26 in the lever. This locking plate 24 is fashioned with a notch 27 and an end cam or beveled face 28. The relative arrangement of the locking pin and locking plate are shown in Figures 3 and 4 where the pawl lever is in unlocked position, with its locking pin carried by the lever disposed between the two resiliently connected levers 17 and 18. When the pawl lever is swung to position to lock the pawl against the teeth of the ratchet wheel, the locking pin 14 rides over the cam face 28 to spread the two resiliently connected levers and as the pin leaves the cam, the former slips into the notch 27. In this position the pawl has locked the ratchet wheel against movement and the pin has locked the pawl lever against swinging movement.

To unlock the pawl by disengaging the pin from its notch, the swinging movement

of the pawl lever will be sufficient to spread the resiliently supported levers against the tension of the spring 20 and permit the pin to pass outwardly toward the free ends of the levers. The levers 17 and 18 rock on their pivot posts to compensate for the swinging movement of the pin on its pawl lever. The tension of the spring 20 holds the pin in locked position between the two locking levers.

Having thus fully described our invention, what we claim as new and desire to secure by Letters Patent is—

1. The combination with a pawl lever and its pin, of a pair of resiliently-connected oscillatable levers, means co-acting with the pin for spreading the levers and means co-acting with the pin for retaining the latter in locked position.

2. The combination with a pawl lever and its pin, of a pair of resiliently-connected oscillatable levers, a locking plate on one of said levers, a cam face on said plate and a locking notch on said plate for co-action with the pin.

3. The combination with a pawl-lever and its pin, of a pair of oscillatable levers and a tension device for normally retaining said levers in parallel position, a locking plate, means for retaining said plate at the inner side of one of said oscillatable levers, a cam face on said plate and a locking notch on said plate for co-action with the pin.

In testimony whereof we affix our signatures.

MAURICE E. WRIGHT.
ALFRED M. BRADEN.
